INTERNAL COMBUSTION ENGINE

Albert Naccache, Beirut, Lebanon

Application March 8, 1939, Serial No. 260,565
In Lebanon March 8, 1938

14 Claims.

(Cl. 123—75)

The present invention relates, in a general manner, to explosion and internal combustion engines of all kinds.

The object of the invention is to provide an engine of this kind of higher efficiency than the engines made up to the present time, owing to a better utilization of the different parts of the working cycle of the engine.

The invention is based upon the following considerations:

The compression and expansion curve, in the working diagram of explosion and internal combustion engines, shows that, over certain portions thereof, corresponding to the beginning of the compression and the end of the expansion, an important variation of volume produces but little work. Now, in the engines of the present time, this expansion and compression work is performed in the part of the engine located between the end of the piston and the cylinder head, that is to say in a very expensive device designed for effecting a much more important work. This involves a defective utilization of the power per mass unit. In order to obviate this drawback, it is therefore necessary to make use of suitable devices, of light weight and low cost, for performing the portions of the work which necessitate the displacement of a considerable volume while absorbing or producing but a small amount of energy.

Consequently, according to the present invention, the preliminary compressions, which absorb a small amount of work but require a considerable volume displacement, are effected in parts of the engine which, up to now, performed no physical function. This ensures a substantial increase of power per mass unit, since the portion of the engine located between the piston and the cylinder head is relieved from this work. This pre-compression is, according to the present invention, effected preferably in the engine in part section itself, under the piston, either in the crankcase or in an extension of the cylinder especially arranged for this purpose. The air compressed by the volumetric compressor thus constituted is stored up in one or several reservoirs which constitute a reserve of compressed air, and in also the engine cylinder finds pre-compressed feed air at the desired times during the working cycle of the engine.

In a four stroke engine, the portion of the engine located between the top part of the piston and the cylinder head will therefore work according to the ordinary four-stroke cycle, and the compressing device operatively connected with

the cylinder will work as a two stroke compressor the cyclic speed of which is twice as fast as that of the ordinary motor device with which it is associated.

On the other hand, in an ordinary motor the increase in pressure at the end of the compression stroke and the correspondingly improved efficiency of the motor is checked due to the rise in temperature occasioned precisely by the increased pressure. In order to relieve this checking effect the feeding matter having already been strongly compressed within a space distinct from that in which final compression is effected, is cooled by forcibly driving same through the piston which acts as a refrigerating chamber. After leaving the piston and preceding its introduction into the space where final compression takes place, the feeding matter is subjected to an additional cooling treatment. Expansion may eventually be accomplished in separate devices which may be arranged in series in a manner similar to that described heretofore in connection with the method of compressing the feeding matter.

In applying the above theoretical considerations, three distinct motor types may be practically realized:

(1) A motor with single-acting cylinders in which preliminary compression is accomplished within the motor casing.

(2) A motor with cylinders having lower cylinder heads in which preliminary compression is accomplished in the extension of the cylinder blocked by a lower cylinder head.

(3) A compound motor formed by the combination of cylinders with lower cylinder head.

The motors with single-acting cylinders or with lower cylinder head may be used and have given interesting practical results, but the compound combination, suitably realized by the use of cylinders with frontal cylinder heads, constitutes the main object of the present invention.

Other features of the present invention will result from the following detailed description of some specific embodiments thereof.

Preferred embodiments of the present invention will be hereinafter described, with reference to the accompanying drawings, given merely by way of example, and in which:

Figs. 1 and 1a, which complete each other, correspond to an axial vertical section of the engine according to the present invention, with the pre-compression performed on the inside of the engine crankcase;

Fig. 2 is a detail plan view of the piston of the engine in part section of Figs. 1 and 1a;

Fig. 3 is a sectional view on the line III—III of Fig. 2;

Fig. 4 is a bottom view of a detail of the piston and a sectional view on the line IV—IV of Figs. 1—1a;

Fig. 5 also shows a detail of the valve arrangement of the compressor, and is a sectional view on the broken line V—V of Fig. 1;

Fig. 6 also shows the valve arrangement disclosed by Fig. 5, and is a sectional view on the line VI—VI of Fig. 1;

Fig. 7 is a vertical axial section of an engine in which the pre-compression is effected not in the crankcase, but in a space especially provided for forming a compressor, in line with the cylinder of the engine.

In Fig. 1, which shows a four stroke engine of the usual type, reference numeral 10 designates the cylinder, 11 the piston, 12 the inlet valve, 13 the connecting rod and 14 the crankcase. According to the present invention, I reduce the volume of the part of the cylinder above the piston and the volume available in the crankcase in the following manner: The space 15 located above the middle wall 16 of the piston is closed by a piston head 17 screwed in the upper part of the piston so as to be flush with the top edge thereof. Above the middle wall 16, the boss 18 of the connecting rod end is covered with an aluminium or copper sheet 19, fixed on the wall in a fluidtight manner, but leaving between it and boss 18 the minimum play necessary for the free movement of the connecting rod. The feed air on its way to the cylinder will flow through space 15, so that said air will act for cooling the piston from the inside. In order to obtain this cooling action, I fix on the top of plug 17 a thin plate 20 of aluminium or copper, provided with a plurality of ribs 21, preferably slightly curved as shown by Fig. 4 for effecting a good distribution of air along their own faces and also along the end element secured to the piston. The general direction of these ribs or fins corresponds to that of the feed air stream.

The inside volume of crankcase 14 is reduced as follows:

On the inside of the piston and under the middle wall 16, there is fixed, on either side of the axial plane in which connecting rod 13 is moving, a piece 22 (Fig. 3), of fluidtight character and made of metal, with bulging parts 23 (Fig. 1) which occupy a certain partial volume between the small faces of the connecting rod and the corresponding opposed faces of the piston. The section of this piece 22 is visible on Fig. 1.

On the inside of the crankcase, I provide, around the cylindrical periphery of the crankshaft, a ring 24 made of a metal having a certain elasticity and which fits in a housing provided in the crankshaft. This elastic ring is split and it bears through its ends 25 on the outer faces of journal 26. This device is applied to the two inner cheeks of the cylindrical crankshaft. Owing to the reduction thus obtained of the inner space of the crankcase, the compressor ensures the degree of compression necessary for obtaining the desired result.

The valve system of the compressor may be of any kind, with positively controlled valves or not. A preferred embodiment of this system is the rotary device shown by Figs. 1, 5 and 6 of the drawings. On a secondary shaft 27, rotating at the same speed as the driving shaft, there is keyed a rotary cylindrical distributor 28, turn-

ing in a sleeve 29 on the inside of the body of the distributor, 30, secured on the side of the engine. In the distributor 28, there are provided two passages or channels, to wit, a first one 31, called an inlet passage, relatively wide and extending over a suitable angle for connecting the inlet conduit 32, which opens to the atmosphere, with the inlet orifice 33 which opens into the crankcase, and another one, 34, slightly narrower, visible in Figs. 5 and 6, adapted to connect conduit 35, coming from the crankcase, Fig. 6, with the discharge conduit 36 visible on Fig. 6. Reference numeral 37 designates a channel for oil under pressure, for lubrication of the distributor. If desired, a suitable third passage or channel may be provided in the distributing device.

The discharge conduit 36 is connected through a suitable channel 38 (Fig. 1) with a first reservoir 39 which constitutes a reserve of air. This reservoir communicates through an outlet passage 40 with an orifice 41 provided in the wall of cylinder 10. At the same level as orifice 41 and diametrically opposed thereto, there is provided in the wall of cylinder 10 an aperture 42 opening into a second reservoir 43 the upper part of which communicates with the conduit 44 through which the inlet valve 12 of the engine is fed with fuel mixture. This reservoir 43 is preferably provided with any known cooling device shown at 45. The first mentioned reservoir may be cooled if deemed necessary.

In piston 11 are provided two orifices 46 and 47, diametrically opposed to each other and located at the same level, both of these orifices opening into chamber 15 and being adapted, for a given position of the piston, to communicate simultaneously with the apertures 41 and 42 of the wall of the cylinder.

The device above described operates in the following manner:

During a part of the downward stroke of piston 11, the rotary distributor 28 separates the inner space of the casing both from the outer atmosphere and from the discharge conduit 36. The air present in the crankcase is compressed. When the compression has reached the desired degree, determined by the amplitude and the position of the passages 31 and 34 of the distributor, the inside of the crankcase is connected with 34 and the discharge conduit and compressed air is sent into the first reservoir 39. During the upward stroke of piston 11, the inside of the crankcase again communicates with the outer atmosphere through orifice 33 and the passage 31 of the distributor which, at this time, is located opposite this orifice 33 and the air inlet 32. Suction takes place and ceases when piston 11 is nearing the end of its upward stroke, at which time distributor 28 again closes the orifice 33.

The compressed air stored in the first reservoir 39 may be sent directly to the inlet valve 12. However, it has been found that it is preferable to provide a second reservoir, or intermediate reservoir 43, chiefly in order to create means for cooling piston 11 from the inside. Piston 11 is provided, as above explained, with two orifices 46 and 47 diametrically opposed to each other and provided in the wall thereof. Every time piston 11 is at the end of its downward stroke, as shown by Figs. 1 and 1a, these orifices 46 and 47 are located opposite the apertures 41 and 42 of the cylinder wall. A communication is then provided between reservoirs 39 and 43 and air

on its way to reservoir 43 passes through the chamber 15 of the piston, passing metal sheet 19 and fins 21, thus ensuring an efficient cooling of the piston from the inside.

Fig. 7 shows another embodiment of the invention, according to which the preliminary compression, instead of taking place on the inside of the crankcase, is performed in the lower part of the cylinder itself, which then acts as compressor cylinder. This arrangement implies certain modifications of the engine. Piston 11 is identical, as a whole, to that of a steam engine, as shown by Fig. 7, but it is more especially arranged in such manner as to give the result according to the present invention. In particular, it is provided, at the top of the added end part 17 screwed thereon, with fins 21. It also includes two orifices 46 and 47, as above explained, for coming opposite the orifices 41 and 42 of the cylinder wall. On the other hand, a supplementary inlet 48 is provided for air, including a small deflector 49, which sends the air entering the passage toward the bottom part of the piston so as to cool it. Radial ribs 50 are provided in the portion of the piston located at the level of this orifice 48. Cylinder 10 is closed, at the bottom, by an end piece 51 through which passes, with the interposition of a packing member, piston rod 53 connected with a cross-head 54 sliding between guideways 55 provided on the engine frame. This cross-head 54 is connected in the usual manner to the driving connecting rod 56. The compressor, constituted by piston 11, the lower part of cylinder 10 and end part 51, is provided with the same distribution system as that of Fig. 1. In other words, it includes a rotary distributor 28 which connects the inside of cylinder 10 alternately with the outer atmosphere and reservoir 39. The engine is provided with the two reservoirs 39 and 43 and its operation, concerning the use of pre-compression, is that described with reference to Figs. 1 and 1a. Distribution by means of a rotary valve can, of course, be replaced by any valve distribution system of a known type, as shown by way of example by Fig. 8, which shows a valve 57 controlled by a lever 58 and a cam 59.

In the embodiment of the invention illustrated by Fig. 7, oils which may have penetrated into the piston through apertures 46 and 48 are evacuated toward the guideways through a central channel 60 of the piston rod 53, communicating at the top through suitable apertures with the inside of the piston end, and at the bottom, through other apertures, with the upper face of the cross-head, from which place the oil is led toward slideways 55.

Some of the many advantages of the invention are the following: The power per unit of mass and the field of utilization are considerably increased, as compared with those of the engines used at the present time. This results mainly from the fact that the cooling of the piston is far beyond the cooling that could be obtained up to the present, the increase in cooling being approximately ten times greater in compound engines. Also, in compound engines, preliminary compression and cooling of the feeding matter enables of reducing its volumetric value in the proportion of at least six to one before its admission to the upper part of the high-pressure cylinder a temperature of only 15° C. above the room temperature, while in all other engines this temperature, with the same volumetric decrease is about 240° C. above the normal tem-

perature. Under these conditions it becomes possible to considerably increase the final pressure and therefore the efficiency of the engine, as well in explosion motors as in internal combustion engines. The cost of construction per unit of power is greatly reduced. The cruising radius is much greater, in the case of engines applied to aviation and automobiles, and, especially, in the case of automobile vehicles, the cost of transportation is reduced.

In a general manner, while I have, in the above description, disclosed what I deem to be practical and efficient embodiments of the present invention, it should be well understood that I do not wish to be limited thereto as there might be changes made in the arrangement, disposition and form of the parts without departing from the principle of the present invention as comprehended within the scope of the appended claims.

What I claim is:

1. A four-stroke internal combustion engine which comprises, in combination, at least one cylinder, two reservoirs, located on opposed sides of said cylinder respectively, an inlet conduit for said cylinder, a hollow piston movable in said cylinder, means, operatively connected with said piston, for compressing air into one of said reservoirs, and means for connecting the other reservoir with said inlet conduit, said piston being adapted to connect said two reservoirs with each other for a portion of the stroke of said piston.

2. A four-stroke internal combustion engine which comprises, in combination, at least one cylinder, two reservoirs, located on opposed sides of said cylinder, respectively, an inlet conduit for said cylinder, a hollow piston movable in said cylinder, a two-stroke compressor including said piston adapted to work with a cyclic speed equal to twice that of said engine, for compressing air into one of said reservoirs, and means connecting the other reservoir with said inlet conduit, said piston being adapted to connect said two reservoirs with each other for a portion of its stroke.

3. A four stroke internal combustion engine, which comprises, in combination, at least one cylinder, two reservoirs, located on opposed sides of said cylinder, respectively, an inlet conduit for said cylinder, a hollow piston movable in said cylinder, a compressor, including said piston, a crankcase for said engine, and means for filling a portion of said crankcase for reducing the inner volume thereof, for compressing air into one of said reservoirs, and means connecting the other reservoir with said inlet conduit, said piston being adapted to connect said two reservoirs with each other for a portion of its stroke.

4. A four stroke internal combustion engine, which comprises, in combination, at least one cylinder, two reservoirs, located on opposed sides of said cylinder, respectively, an inlet conduit for said cylinder, a hollow piston movable in said cylinder, a compressor including said piston for compressing air into one of said reservoirs, a rotary distributor operatively connected with said engine and turning at the same speed associated with said compressor, and means connecting the other reservoir with said inlet conduit, said piston being adapted to connect said two reservoirs with each other for a portion of its stroke.

5. A four stroke internal combustion engine, which comprises, in combination, at least one cylinder, two reservoirs located on opposed sides of said cylinder, respectively, an inlet conduit for

said cylinder, a hollow piston movable in said cylinder, a compressor, including said piston, a crankcase for said engine, and means for filling a portion of said crankcase for reducing the volume of the inside thereof, for compressing air into one of said reservoirs, a rotary distributor operatively connected with said engine and turning at the same speed associated with said compressor, and means connecting the other reservoir with said inlet conduit, said piston being adapted to connect said two reservoirs with each other for a portion of its stroke.

6. A four-stroke internal combustion engine which comprises, in combination, at least one cylinder, two reservoirs located on opposite sides of said cylinder respectively, an inlet conduit for said cylinder, a hollow piston movable in said cylinder, means, operatively connected with said piston, for compressing air into one of said reservoirs, and means for connecting the other reservoir with said inlet conduit, said cylinder being provided with apertures communicating with said reservoirs, respectively, and said piston being provided with ports adapted to cooperate with said apertures, respectively, so as to connect said two reservoirs with each other for a portion of the stroke of said piston.

7. A four stroke internal combustion engine which comprises, in combination, at least one cylinder, two reservoirs, located on opposite sides of said cylinder, respectively, an inlet conduit for said cylinder, a hollow piston movable in said cylinder, a two-stroke compressor including said piston adapted to work with a cyclic speed equal to twice that of said engine, for compressing air into one of said reservoirs, and means connecting the other reservoir with said inlet conduit, said cylinder being provided with apertures communicating with said two reservoirs respectively, and said piston being provided with ports adapted to cooperate with said apertures, respectively, so as to connect said two reservoirs with each other for a portion of the stroke of said piston.

8. A four stroke internal combustion engine which comprises, in combination, at least one cylinder, inlet means for said cylinder, a hollow piston movable in said cylinder, a transverse partition wall extending through said piston below the piston head and providing a chamber therebetween, means, operatively connected with said piston, for compressing air, means for conveying the air compressed by said means through the chamber in said piston to said inlet means, and cooling means carried upon the inner walls of said chamber in said piston, said cooling means including fins, composed of a metal different from said piston and extending throughout said chamber in the direction of the flow of compressed air therethrough.

9. A four stroke internal combustion engine which comprises, in combination, at least one cylinder, two reservoirs, located on opposed sides of said cylinder, respectively, an inlet conduit for said cylinder, means, operatively connected with said piston, for compressing air into one of said reservoirs, means for connecting the other reservoir with said inlet conduit, said cylinder being provided with two diametrically opposed apertures communicating with said reservoirs, respectively and said piston being provided with two ports adapted to cooperate with said two apertures, respectively, so as to connect said two reservoirs with each other for a portion of the

stroke of said piston, and cooling fins carried by the inner wall of said piston and extending in the direction from one of said ports to the other.

5 10. A four stroke internal combustion engine which comprises, in combination, at least one cylinder, two reservoirs, located on opposed sides of said cylinder, respectively, an inlet conduit for said cylinder, a hollow piston movable in said cylinder, means operatively connected with said piston, for compressing air into one of said reservoirs, means for cooling at least one of said reservoirs, and means for connecting the reservoir opposed to that into which air is compressed by said compressing means with said inlet conduit, said piston being adapted to connect said two reservoirs with each other for a portion of the stroke of said piston.

20 11. A four stroke internal combustion engine which comprises, in combination, at least one cylinder, two reservoirs, located on opposed sides of said cylinder, respectively, an inlet conduit for said cylinder, a hollow piston movable in said cylinder, a compressor, including an extension of said cylinder and a piston rigidly connected with said first mentioned piston, for compressing air into one of said reservoirs, and means connecting the other reservoir with said inlet conduit, said piston being adapted to connect said two reservoirs with each other for a portion of its stroke.

25 12. A four stroke internal combustion engine which comprises, in combination, at least one cylinder, two reservoirs, located on opposed sides of said cylinder, respectively, an inlet conduit for said cylinder, a hollow piston movable in said cylinder, a compressor, including an extension of said cylinder and a piston rigidly connected with said first mentioned piston, for compressing air into one of said reservoirs, a rotary distributor operatively connected with said engine and turning at the same speed associated with said compressor, and means connecting the other reservoir with said inlet conduit, said piston being adapted to connect said two reservoirs with each other for a portion of its stroke.

30 13. A four stroke internal combustion engine which comprises, in combination, at least one cylinder, two reservoirs, located on opposed sides of said cylinder, respectively, an inlet conduit for said cylinder, a hollow piston movable in said cylinder, a compressor, including an extension of said cylinder and a piston rigidly connected with said first mentioned piston, for compressing air into one of said reservoirs, a rotary distributor operatively connected with said engine and turning at the same speed associated with said compressor, and means connecting the other reservoir with said inlet conduit, said cylinder being provided with two diametrically opposed apertures communicating with said reservoirs, respectively, and said piston being provided with two ports adapted to cooperate with said two apertures, respectively, so as to connect said two reservoirs with each other for a portion of the stroke of said piston.

35 14. A four stroke internal combustion engine according to claim 13, in which said piston is provided with a supplementary orifice, and a deflector associated therewith, for sending scavenging air onto the end of said piston.
